WINDOW SHUTTER

Harvey R. Patton, Creve Coeur, Mo.

Application March 7, 1955, Serial No. 34,913

Term of patent 7 years

(Cl. D13—1)

Fig. 1

Fig. 3

Fig. 1 is a frontal elevational view of a window shutter showing my new design;

Fig. 2 is a side elevational view; and

Fig. 3 is an end view looking upward toward the lower end of Fig. 1.

I claim:

The ornamental design for a window shutter, as shown.
